[57] CLAIM

The ornamental design for bottle, as shown and described.

DESCRIPTION

FIG. 1 is a front elevational view of a bottle embodying the design, the bottle having a transparent vertical front face, and the figure showing the appearance of the interior of the bottle as seen through that face;
FIG. 2 is a side elevational view of the bottle;
FIG. 3 is a rear elevational view of the bottle;
FIG. 4 is a top plan view of the bottle; and
FIG. 5 is a bottom plan view of the bottle.

FIG. 1.

FIG. 2.

FIG. 3.

FIG. 4.

FIG. 5.
